UNITED STATES PATENT OFFICE.

WILFRED B. GODDARD, OF SAN FRANCISCO, CALIFORNIA, ASSIGNOR TO THOMAS DAY COMPANY, OF SAN FRANCISCO, CALIFORNIA, A CORPORATION OF CALIFORNIA.

ELECTRIC-LIGHT-BOWL HANGER.

Application filed May 4, 1921. Serial No. 466,692.

To all whom it may concern:

Be it known that I, WILFRED B. GODDARD, a citizen of the United States, and a resident of the city and county of San Francisco, 5 State of California, have invented a certain new and useful Electric-Light-Bowl Hanger, of which the following is a specification.

This invention has reference to electric light fixtures and more particularly to suspended bowl fixtures.

It is one of the objects of the present invention to provide an improved supporting means for carrying, in a suspended position, a translucent or other illuminating bowl in 15 which there may be arranged a cluster of electric lamps. An important object of the invention is to provide for the rigid interlocking of the supporting means with the rim of the bowl so that without detaching 20 any of the supporting means from the bowl proper, one or another of a series of suspending chains may be disconnected from a respective hook forming a part of the supporting means or hanger, and so that the 25 bowl may be tilted down edgewise or laterally to facilitate access to the interior thereof for cleaning or other purposes.

A further object of the present invention is to provide a rigid suspending and 30 supporting structure in the form of an attachment adapted to be readily secured to the rim of a bowl and which will facilitate and enable the mounting of auxiliary, or ornamental, or exterior light, attachments to the 35 bowl or to the supporting means.

Another object of the invention is to provide a supporting means that can be easily collapsed and compactly folded for packing and shipping, and readily adjusted to, and 40 lock in an adjusted position for supporting an attached bowl.

Another object of the invention is to provide a standard equipment or supporting means which, while being made of uniform 45 size and of interchangeable structural features, also provides for ready adaptation of a given standard equipment to light bowls of different dimensions by the provision of a set of arms of stock size, which are adapted 50 to be severed or broken at predetermined points indicated by weakened portions of the arms at the desired points to render them shorter than the stock or standard length.

Another object of the present invention

is to provide a supporting means attachable with equal facility to suspension chains or to a central supporting rod as may be desired without change of construction of the several parts.

A still further object of the present invention is to provide in a supporting means for bowls, an improved safety chain hook which will permit of the relative tilting or swinging of the engaged link of a chain 65 with respect to the hook without danger of the disengagement of the hook and the links. In this connection it is a further object to provide a chain hook having a contracted mouth to restrain disengagement of the 70 chain and, further, to provide a chain hook having, opposite the end of the hook, a stop lug or shoulder to prevent disengagement of the chain when it is clear of the hook curve.

The invention possesses other objects and features of advantage, some of which, with the foregoing, will be made manifest in the following description of the preferred form of the invention which is illustrated in the drawings accompanying and forming part 80 of the specification. It is to be understood that it is not intended to limit the invention to the embodiment shown by the said drawings and description as variations may be adopted within the scope of the invention as 85 set forth in the claims.

Fig. 1 is a side elevation of a bowl suspended by means of chain, the bowl being broken away to show a portion of the supporting means.

Fig. 2 is a side elevation of a bowl suspended by means of a central tube fixture.

Fig. 3 is a perspective showing an erected bowl hanger or support; the bowl being omitted for clearness.

Fig. 4 is a perspective showing the dismounted and disconnected actuating elements of the hanger.

Fig. 5 is a perspective of one of the safety hooks.

Fig. 6 is a perspective of a central rod engaging stirrup.

In electric light fixtures of the type embodying a suspended bowl, it is very desirable to provide means which will enable 105 the bowl to be safely disengaged from one of the supporting chains, when these are used, so that the bowl can be tilted or suspended on the remaining chains to enable access to the interior of the bowl for clean- 110

ing and various other purposes. Further it is very desirable to provide an improved hook attachment to a suspending chain, so that the hook will not be freely disengaged 5 either during the mounting of the bowl, or during the cleaning or other necessary manipulation thereof. Again, it is desirable to provide a fixture which can be substantially permanently and rigidly mounted in 10 the bowl by attachment to rim thereof, and yet provide for the connection of the supporting means either to suspension chains or to a central suspending rod or tube.

The present invention consists of a unitary, organized structure forming a suspension and supporting means capable of being compactly arranged for storage, packing, and shipment, and yet readily assembled and erected in place on a given bowl, such 15 as is indicated at 2 in Figs. 1 and 2 which may be provided with any suitable type of rim adapted to be engaged with a complementary form of hook, one type of which is here disclosed. The hooks 20 3 are provided on the outer ends of substantially radial arms 4 of which any suitable number may be utilized in a set. Preferably the hooks 3 are adjustably mounted on the outer ends of the rods or arms 4 and 25 may be secured at the desired position as by means of set-screws 5. The set of rods or arms 4 are adapted to be simultaneously and uniformly, radially shifted inwardly or outwardly to secure an interlock of the 30 parts on the rod ends with the rim of a bowl, and preferably means are provided by the manipulation of which the several arms are concurrently shifted and locked in their given position.

40 In the present construction the inner ends of the arms 4 are mounted for guided movement upon a bearing member 6 which is shown as provided with upwardly extending and equally spaced circumferential lugs 45 7 through which the arms 4 extend and are arranged in a common plane. The bearing plate is preferably in the form of a flat disc through which is passed a central screw 8 forming a pivot about which is rotatable a 50 flat plate or disc 9 from which extends a handle or lever 10, in the plane of the disc 9, which latter lies just above the center bearing 6.

The inner ends of the arms 4 are suitably 55 connected to the disc 9 to be actuated thereby when the latter is rotated, so that the arms will shift longitudinally and substantially radially with respect to the pivot 8. A simple, practicable and inexpensive form 60 of connection is obtained by bending the inner ends of the arms 4 upwardly at right angle, as 4^a, to pass through apertures 9^a in the disc 9. By resting the inner ends of the arms 4 on the top of the center plate 6 and 65 applying the disc 9 over the upturned ends

of the arms, the pivot screw 8 may be utilized to hold the disc 9 and the arms in proper assembled relation when lock nut or nuts 11 are screwed up on the lower end of the screw 8, below the center plate 6. 70

In operation when the actuating disc 9 is rotated by the handle 10, so as to bring the ends 4^a of the arms 4 into juxtaposition with respective guides 7 the arms are moved outwardly and, conversely, when the ends 4^a 75 are moved away from the bearing lugs 7 the arms 4 are drawn inwardly there-through.

When the several arms have been adjusted to the desired position to securely grapple 80 with the rim of the bowl they may be locked securely by suitable means. A form of means may include an extension or part 12 secured to the arm 10 and extending laterally therefrom to interlock with an adjacent arm 4, as clearly shown in Fig. 3. The locking element 12 may consist of a piece of sheet metal having its upper edge notched as at 13 to receive the contiguous arm 4 when the parts are in position to be locked. The 85 lever 10 and the part 12 are relatively yieldable with respect to the arm 4 that is engaged so that disengagement may be secured by simply depressing the locking member 12 to carry it out of engagement 90 with the contiguous arm 4. 95

In case the bowl is to be suspended by means of chains C, then the bowl hooks 3 are preferably provided with chain hooks 15 extending upwardly to receive the contiguous chain links. It is one of the purposes of the present invention to provide a chain hook which will give a desirable degree of safety against accidental slipping and disengagement of the chain from the hook, when the engaged link is thrown to certain angular positions with respect to the hook. In Fig. 5 a preferred form of hook is shown as comprising a part 15 with its end laterally enlarged or made of T 100 form as shown at 16, the length of the head portion being sufficiently greater than the slot of the links as will prevent the links from slipping off the end of the hook. 110

An additional security is provided by provision of a stop lug 17 disposed opposite the hook end 16 and forming therewith a contracted mouth 18. 115

One or more electric lamp sockets or other ornamental attachments or devices may be secured to the hanger, for providing for the attachment of these appliances. In the present case the bowl hook 3 is provided with a downwardly extending arm 3^a for any desired appliance and the upper arm of the 120 hook 3 is threaded at 3^b to receive an appliance. 125

Instead of supporting and suspending the fixture by chains C, the rigidly mounted supporting or hanging means is adapted to 130

be interlocked with a central drop tube or other pendant P as indicated in Fig. 2, in which case the pendant device P is provided at its lower end with a connection in a form

5 of a cap or plate 19 having a plurality of downwardly extending and circumferentially spaced engaging hooks 20 to be passed underneath the inner portions of the arms 4 to hold the same; the hooks 20
10 being disposed in a position to pass over the outer edge of the center plate 6 of the hanger.

The hanger organization may be constructed or assembled as a unit utilizing a
15 set of arms 4 which are of stock length for given sizes of bowls. In order to provide for the ready adaptation of a given stock size of hanger organization to a bowl of different size the several arms 4 are weakened
20 transversely at points along the arm so that they may be broken at any of the weakened points to provide a shorter arm of desired length; such weakening being formed or obtained as by notches 4^b along
25 the arm, at any of which, the arm can easily be broken.

When, for any reason, it is desired to have access into the interior of the bowl it is only necessary to detach one of the chains from
30 its hook and the released edge of the bowl lowered while the bowl is suspended by the remaining hooks and chains. If it is desired to dismount the bowl together with the organized hanger then all of the chains are
35 disconnected from their hooks and the bowl lowered away. The bowl alone may be disengaged from the several hooks by releasing the locking device and throwing the actuating disc or part 9 in such position as

will clear the hooks from the rim of the 40 bowl still leaving the organized hanger connected to its suspension means as the chains or the pendant P.

What is claimed is:

1. An electric light bowl hanger comprising- 45 a bearing member, substantially radially disposed arms, bearing in said member, bowl rim engaging hooks on the outer ends of said arms, a plate pivoted to said bearing member and to which the inner ends of said arms are pivoted, a lever extending from said plate for rotating the plate with respect to the bearing member and means for securing the lever to one of the arms. 50

2. An electric light bowl hanger comprising- 55 a bearing member, apertured upstanding ears on said member, arms extending through said ears and having their inner ends disposed over said member, an actuating element pivoted to said member and to which the inner ends of said arms are pivoted, bowl rim engaging hooks on the outer ends of said arms and means for rotating the actuating element to slide the arms through the ears. 60

3. An electric light bowl hanger comprising- 65 a bearing plate, a series of arms guided in a common plane on the plate for longitudinal adjustment, a disc pivoted on the plate and connected to said arms for adjusting them uniformly, and means for locking the arms when adjusted and including a lever on said disc having a hooking engagement with one of the arms. 70

In testimony whereof, I have hereunto set 75 my hand.

WILFRED B. GODDARD.
